UNITED STATES PATENT OFFICE.

JAMES LONG, OF WYANDOTTE, KANSAS.

STEAM-BOILER.

SPECIFICATION forming part of Letters Patent No. 256,489, dated April 18, 1882.

Application filed April 27, 1881. (Model.)

To all whom it may concern:

Be it known that I, JAMES LONG, a citizen of the United States, residing at Wyandotte, county of Wyandotte, and State of Kansas, have invented a new and useful Improvement 5 in Steam-Boilers for Locomotive-Engines, of which the following is a specification.

The invention relates to locomotive-boilers, and has for its object increased effectiveness 10 of draft and more perfect and economical combustion of fuel than has heretofore been effected.

The improvement consists in constructing the furnace of two distinct and independent fire-boxes separated from each other by a water-space. These fire-boxes communicate with the smoke-box by flues in the usual way. A partition in the smoke-box isolates the exhaust-nozzles and separates the two systems 20 of flues from each other, each system discharging into a separate smoke-stack. Separate grates, ash-pans, and fire-doors are used in these furnaces, thus making each complete in itself and independent of the other.

In the accompanying drawings, in which similar letters of reference are used to designate like parts, A represents the fire-boxes; B, the ash-pans; D, the fire-doors, and S the stacks; P, the partition-wall in smoke-box; N, the exhaust-nozzles, and W the water-space 30 partition separating the fire-boxes.

Figures I and II are vertical and longitudinal sections of boiler, showing the disposition of parts. In Fig. III the back end of boiler 35 is removed to show fire-boxes in position, one of which is shown partly in section, revealing the flue-sheet at the back. Fig. IV is an end view of boiler, showing fire-doors. The manner of constructing and connecting the fire-door openings is also shown in Figs. I and II. Figs. V and VI are transverse sections of the 40 smoke-box, showing the partition P, the smoke-stacks S and S, the exhaust-nozzles N and N, and the disposition of the two systems of flues on either side of partition. The partition P isolates the exhaust-nozzles N and N and separates the two systems of flues from each other, and forms the dividing-wall between the stacks S and S. In Fig. VI the smoke-box is shown enlarged by a ring, I, surrounding 45 the shell of boiler. This enlargement is advantageous where additional room may be required for the construction of duplicate stacks, lifting-pipes, &c., as in the improvement above 50 described.

The advantages of the above combination of parts are the following: first, more powerful and effective draft, each furnace and set of flues being operated upon by the full force of the divided blast hitherto used for stimulating 60 double-flue and grate area; secondly, the prolonged interval between exhausts due to the division of the blast effects a more thorough and intimate combination of air and fuel, generating greater heat and retaining the same 65 long enough in contact with flue-area to secure the best results of combustion; thirdly, the division of flue-area into two equal parts renders the draft through the flues more uniform and less local than heretofore. 70

Among the minor advantages of the combination may be mentioned the additional area gained in the partition W; the superior circulation of water, due to the water-space separating the two furnaces and systems of flues; 75 the reduced area of the crowns of the fire-boxes, which allow of being braced without the use of crown-bars and other incumbrances; and, finally, the improved efficiency and service of the engine constructed with the duplicate boiler, which may at the option of the engineer be run with either furnace singly or with both, as may be necessary. Thus, if one of the furnaces be damaged or the connecting-flues be impaired so as to disable the engine 80 under ordinary circumstances, its life may be sustained by running with the remaining furnace without inconvenience. 85

I am aware that the double furnace or fire-box having a common grate and ash-pan has 90 been used in England on locomotive-engines; and I am also aware that a double stack for locomotives is not a novelty; but these I do not claim as new or original; but

What I do claim as my invention is— 95
1. A locomotive-boiler divided into two divisions longitudinally by a vertical partition, each of said divisions being capable of performing the service of an independent boiler, and both having a common shell, in the manner shown and described.

2. The combination, in a locomotive-boiler, of the divided fire-box, the divided smoke-box, and the independent exhaust-nozzles and smoke-stacks, so arranged that each may be 105 used alternately or separately, substantially as shown and described.
